PREDETERMINING DISPENSER

Einar Thoresen and George J. Genung, Pittsburgh, Pa., assignors to Pittsburgh Equitable Meter Company, Pittsburgh, Pa., a corporation of Pennsylvania

Application February 15, 1936, Serial No. 64,118

14 Claims. (Cl. 221—101)

The present invention relates to dispensing apparatus for delivering a predetermined quantity of fluid and automatically cutting off the flow of fluid when the desired quantity of fluid has been delivered.

It is an object of this invention to provide an apparatus which is simple in construction and may be easily set for each delivering operation.

Another object is the provision of a valve latching mechanism operated by a predetermining counter and which can be tripped by a very slight force.

Another object is the provision of a predetermining counter which can be set by a simple manipulation for delivery of the desired quantity of fluid.

A further object is the provision of an apparatus wherein the predetermining counter housing can be set at any angular position with respect to the delivery valve.

These and other objects will be apparent from a consideration of the following specification taken in connection with the accompanying drawings and wherein:

Figure 1 is a front elevation of a preferred modification of the invention with the cover plate for the valve latch compartment removed and showing certain parts in section;

Figure 2 is an enlarged detail view of the latch mechanism of the valve;

Figure 3 is a side elevation of certain parts of the latch mechanism looking in the direction of the arrow III of Figure 2;

Figure 3a is a plan view of a detail;

Figure 4 is a plan view of the valve member;

Figure 5 is a side elevation of the register and predetermining counter mechanism, the casing being shown in vertical section;

Figure 6 is a front elevation of the predetermining counter wheel assembly;

Figure 7 is a left side elevation of the units counter driving gear assembly as viewed in Figure 6;

Figure 8 is a section taken on line VIII—VIII through the units counter wheel of Figure 6;

Figure 9 is a left side elevation of the tens counter gear disk assembly;

Figure 10 is a section taken on line X—X through the tens counter wheel of Figure 6 showing the ratchet drive mechanism;

Figure 11 is a front elevation of the tens counter wheel;

Figure 12 is a left side elevation of the tens counter wheel as viewed in Figure 11 in assembled relation with a mutilated transfer pinion;

Figure 12a shows an assembly in vertical section with a modified resetting shaft;

Figure 13 is a rear view of a further modification with the latch in locked position, certain parts being shown in section;

Figure 14 is a top view of a modified valve with certain parts broken away;

Figure 15 is a bottom elevation view on a reduced scale of Figure 13;

Figure 16 is a top elevation view on a reduced scale of the latch mechanism with the cover removed;

Figure 17 is a side elevation on a reduced scale of the latch mechanism in released position;

Figure 18 is a sectional view of a detail;

Figure 19 is a sectional view through the center of the latch pin; and

Figure 20 is an elevation of the stuffing box and valve stem assembly.

20 Referring to the drawings, Figure 1, there is shown a fragmentary elevation of a liquid meter housing 1 having an inlet 2 and an outlet 3 to which is suitably connected a valve casing indicated generally by the numeral 4. The meter 25 may be of any suitable construction or type, the preferred construction being shown and described in the application of Walter H. Parker and Nelson J. Seibert, filed April 9, 1934, Serial No. 719,788. An adapter plate 5 is secured over 30 the distributing chamber of the meter, and a register indicated generally by the numeral 6 is secured to the adapter plate by bolts or in any other suitable manner.

25 The valve casing 4 is divided by a partition 7 having a valve orifice 8 therethrough which is normally closed by a compound valve closure member 9, and shown in Figure 1 as held in open position by a trigger latch mechanism adapted to be released, as will presently be described, 40 when a predetermined quantity of fluid has passed through the meter. The valve closure member 9 has guide ribs 10 extending axially thereof which are adapted to engage the wall of orifice 8 to guide the valve in its axial movement. 45 The valve has an integral hollow cylindrical extension 11 which is threaded adjacent its base, and a soft washer 12 made of rubber or other suitable material surrounding the extension 11 is held in position by a backing washer 13 and a nut 14 threaded on the cylindrical extension.

50 The guide ribs 10 merge at the center and form a space 15 between the ribs which provides a fluid passageway through the valve closure 9, this passageway being adapted to be closed by a 55 smaller valve member 16 of suitable construction.

enclosed within the cylindrical extension 11, suitable openings being provided in the wall of the extension 11 to allow passage of fluid therethrough. A hole 17 is formed through the center of the ribs through which passes a short guide stem 18 attached to the valve 16. The valve 16 has a suitable soft seat 19 adapted to seat against the valve seat 20, and a flange 21 thereon is engaged by a spring 22 which urges the smaller valve 16 and larger valve 9 into closed position. A threaded opening 23 in the valve casing is provided to enable removal and inspection of the valve and this opening is closed by a removable cap 24 threaded therein. The valve operating stem 26 has a head 27 adapted to engage the end of short guide stem 18. The stem 26 passes through a stuffing box 28 of any suitable construction and is received in a plunger 26' which is adapted to be pushed downward manually by the lug 25 on the operating handle 29 which is of any suitable construction and is held in upward position disengaged from plunger 26' by a leaf spring 30.

The valves 9 and 16 are adapted to be held in open position by a latch mechanism which now will be described. The valve casing 4 has a latch chamber 40 covered by a plate 25 (Figure 3) and the operating plunger 26' has a cross head and pin 31 formed thereon which is engaged by the bifurcated ends 32 of the forked bell crank lever 33 rotatably mounted on pin 34 in the latch chamber. The opposite end 39 of the bell crank lever 33 is slotted to receive a roller 35 rotatably mounted on a suitable pin 35' passed through the lever. A second or multiplying bell crank lever 36 is similarly pivotally mounted on a pin 37 parallel to pin 34 and has a track with a portion 41 curved concentrically about pin 35' and a straight portion 38 on arm 42 thereof. The arm 43 of bell crank lever 36 has a rounded end 44. A third bell crank lever 46 is pivotally mounted on pivots 47 and has arms 48 and 50, with a recess 49 in the hub thereof providing a straight track portion indicated at 51. The latch lever 53 is pivoted on a pin 54 at substantially a right angle to the axes of the other levers, and its horizontal arm 55 is adapted to be depressed sufficiently to permit the rounded end of arm 50 of lever 46 to pass thereover and to be latched thereby against return movement. The latch lever 53 has an extension 57 of its arm 56 which is adapted to be moved in tripping direction by a pivoted trip 58 pinned to shaft 60. A wire spring 59 wrapped around rocker shaft 60 and trip 58 constrains extension 57 to the right as seen in Figure 3. Both trip 58 and spring 59 are suitably secured to rocker shaft 60. Rocker shaft 60 is suitably journaled in the valve casing 4 and in a flanged bushing 61 suitably secured to the valve casing. The valves 9 and 16 are shown in open position in Figure 1, and in Figures 2 and 3 the latch mechanism is shown in full lines on an enlarged scale in corresponding position, and in dot and dash lines corresponding to the closed position of the valve.

The trigger latch is adapted to be depressed automatically by the register 6 upon passage of a predetermined quantity of fluid through the meter, as will presently be described. However, an emergency trip is provided so that the valve 70 may be closed manually at any time. This trip comprises a plunger 65 suitably journaled in the valve casing and held outward by a spring 66 so that normally its inner end is not in engagement with extension 56 of lever 53. A sleeve 67 is

5 pinned to the inner end of plunger 65 to hold the plunger and spring 66 in assembled relation. By manually pushing plunger 65 inwardly it engages extension 56 and trips latch arm 55 thus releasing arm 50 to allow the spring 22 to simultaneously close valves 9 and 16.

The register comprises a casing 70 in which is secured a framework 71 carrying the register mechanism, the register case 70 being closed at its bottom by a plate 72. A meter driven shaft 73 passes through a central bushing 74 therein, said shaft being adapted to be driven from the meter 1 by suitable gearing (not shown). The shaft 73 is connected to vertical shaft 75 by an Oldham coupling 76 or any other suitable connection. The shaft 75 is journaled in the frame 71 and carries a bevel gear 77 for driving bevel gear 78 on totalizing counter drive shaft 79 which drives the totalizing counter 80, and a worm 81 co-operating with worm wheel 82 drives unit indicator shaft 83 through a suitable friction coupling.

The reduction shaft 84 which is offset from shaft 79 is frictionally coupled to a gear 85 thereon which is driven from gear 86 on shaft 83. Pinion 87 on shaft 84 drives the integral spur gear and sleeve 88 rotatably secured on shaft 83, and the indicators or dials 90 and 99 are driven by shaft 83 and gear 88 respectively to indicate units and sub-total gallons. The drive for the indicators 89 and 90 is more fully described in the copending application of Nelson J. Seibert and Walter H. Parker filed November 3, 1932, Serial No. 641,098.

A second worm 91 on shaft 75 cooperates with a worm wheel 92 on the predetermining counter driving shaft 93 which is suitably journaled in frame 71, and has a bevel gear 94 secured at its inner end. A plate 96 (Figures 5 and 6) is secured to the frame 71 by suitable screws (not shown) and a plate 95 is secured thereto in spaced relation by a combined spacer and bearing block 96' and top spacers 100 to support the predetermining counter mechanism. An intermediate cross shaft 98 is journaled in suitable bushings in said plates and carries a bevel gear 99 adapted to engage and be driven by bevel gear 94, and a spur gear 101 thereon meshes with the spur gear 102 of the predetermining counter wheel assembly.

The predetermining counter wheel assembly 60 comprises a units counter wheel 103, a tens counter wheel 104 and a hundreds counter wheel 105, all being rotatably journaled on the counter setting shaft 107, although any desired number of counter wheels may be used. The counter wheels 103, 104 and 105 are basically similar, so that only wheel 103 will be described in detail, and the differences of the other wheels thereover will be pointed out. Wheel 103 comprises a numeral cylinder 106 (Figures 6 and 8) preferably made of Celluloid or other suitable material having secured thereon a metal flange 107 with an arcuate notch 110 in its periphery. The corresponding flanges 108 and 109 (Figure 6) of counter wheels 104 and 105 preferably are of progressively increased diameter respectively, and the bottoms of notches 111 and 112 thereof are the same distance from the center as the bottom of notch 110. A metal hub 113 (Fig. 8) extends through the cylinder 106 on which is centered the flange 107, a notched transfer pinion locking plate 114 (Figures 11 and 12) and a toothed transfer plate 115, the latter having a registering notch 116 in its periphery between two teeth. This construction

shown in Figure 12 is common to all of the counter wheels.

The unit counter assembly 103 includes the gear spur 102 (Figures 6 and 7), having a notched plate 117 secured thereto (Figure 7), and a plurality of pawls 118 pivoted on the pins 119 are urged outwardly by the bent leaf springs 120. An internal ratchet wheel 121 (Figure 8) which preferably has forty teeth is secured to cylinder 106, and in assembled position the pawls 118 are urged into engagement with ratchet wheel 121 so that cylinder 106 and plates 114 and 115 thereon are positively driven by gear 102 in one direction. In rotation a tooth of transfer plate 115 engages a mutilated tooth of mutilated transfer pinion 122 which is rotatably journaled on shaft 123 until the notch 116 in transfer plate 115 and locking plate 114 engages a complete tooth of transfer pinion 122. Pinion 122 engages gear 124 of adjacent counter wheel 104 and when pinion 122 is rotated one-quarter of a revolution the counter wheel 104 is rotated one tenth of a revolution. The notch 116 becomes disengaged from pinion 122 leaving two complete teeth engaging the periphery of locking disk 114 to prevent rotation of pinion 122 and gear 124 while the notch 116 is out of engagement with pinion 122.

Gear 124 (Figure 9) of counter wheel 104 carries two pivoted pawls 125 which are urged outwardly by spring 126, and the numeral cylinder of counter wheel 104 (Figure 10) has a notched insert 127 secured thereto about hub 113. When gear 124 is turned by transfer pinion 122 the pawls 125 engage the notches in insert 127 and rotate the counter wheel 104. In a similar manner, the transfer plate 115 on wheel 104 periodically engages mutilated transfer pinion 128 to rotate gear 124 of counter wheel 105. From the foregoing description it will be seen that the counter wheel 104 makes one revolution for ten revolutions of counter wheel 103, and counter wheel 105 makes one revolution for one hundred revolutions of counter wheel 103.

A weight 130 is pivoted on shaft 131 which is journaled in plates 95 and 96, and carries two downwardly extended lugs 132 in which is journaled a shaft 133 carrying three rollers 134, 135 and 136 (Figures 5 and 13). When the register wheels 103, 104 and 105 are all set off of zero, roller 136 rides on the edge of flange 109 and holds the weight 130 in elevated position. When the counter wheels all register zero the rollers 134, 135 and 136 fit into the recesses 110, 111 and 112 respectively, thus permitting the weight 130 to assume its descended position. The weight 130 is connected by a rod 137 to the outer end of link 138 secured on shaft 140, and shaft 140 is coupled to rocker shaft 60 (Figure 1) by a coupling rod 141. The lowermost position of weight 130 is adjusted by screw 142 which engages the top of bearing block 96.

The locking plates 114 on the counter wheels are recessed at 145 (Figure 12) and receive a pivoted pawl 146 which extends into the hole 147 in the hub 113, and is urged inwardly into this position by a hair pin spring 148 in the recess 145. The counter setting shaft 107 has an arcuate notch or recess 149 intermediate its ends, so that when the notch is properly positioned the pawl 146 falls into this notch. An indicator frame 150 (Figure 5) is secured to the setting shaft 107 for longitudinal movement therewith and is so adjusted that when pointer 151 thereon (Figure 1) is opposite a numeral cylinder the

pawl 146 of that particular cylinder has fallen into the notch 149 in shaft 107. An extension 152 is suitably coupled to setting shaft 107 and slidably extends through the casing 70 so that it may be moved longitudinally to properly locate the notch 149 in setting shaft 107. The shaft 107 is utilized to set the counter wheels 103, 104 and 105 to indicate a predetermined quantity to be delivered. If desired, a plurality of notches 149 may be formed in shaft 107 side by side in staggered relation to the pawls 146 so that the amount of longitudinal movement of shaft 107 for setting the counter wheels may be reduced. The indicators 89 and 90 can be reset to zero by means of a side ratchet set back extension 155 (Figure 1) which carries a bevel gear 156 (Figure 5) on its inner end in mesh with a bevel gear 157 secured on unit shaft 83.

In Figure 12a there is shown a counter assembly taken in diametrical section through the pivot of a pawl 146 showing a modified form of resetting shaft. In this figure the counter-wheels 103, 104 and 105 are mounted on a sliding shaft 158, and the counter-wheels are constructed exactly as previously described in connection with Figures 6 to 12. The shaft 158 is shown in position with the notch 159 opposite the pawl 146 of counter-wheel 105 and engaged thereby for resetting operation. With the shaft in this position a notch 159' is formed in the shaft 158 adjacent the notch 159 and intermediate the notch 159 and pawl 146 of counter-wheel 104, and a third notch 159'' is formed in the shaft 158 on the opposite side of pawl 146 of counter-wheel 104. The notches 159, 159' and 159'' are so arranged in staggered relation to the pawls 146 that only one notch can engage one pawl at any time. The advantage of this construction over that shown in Figure 6 is that the resetting operation may be accomplished with a much smaller longitudinal movement of the shaft 158. Upon movement of the shaft 158 to the right for a distance substantially equal to one-third the width of a counter-wheel, the notch 159 is disengaged from its pawl 146 of counter-wheel 105, and the notch 159' is engaged with its pawl 146 of counter-wheel 104, while the notch 159'' is brought closer to pawl 146 of wheel 103 but is still not in engagement therewith. When the shaft 158 is shifted again to the right for a distance of approximately one-third the width of a counter-wheel, the notch 159'' engages the pawl 146 of counter-wheel 103 while the notches 159 and 159' are both disengaged from their respective pawls.

The operation of the apparatus now will be described. Let it be assumed that a quantity of five hundred fifty-five gallons is to be delivered. The setting shaft 107 is moved longitudinally until the pawl 146 of units counter wheel 103 falls into the notch 149 on shaft 107 as indicated by the pointer 151, (Figure 1), and the shaft 107 is then turned counter clockwise as viewed in Figure 5 by means of extension 152 until counter wheel 103 shows the numeral five. During the setting operation pawls 118 (Figure 8) ride over the teeth of ratchet wheel 121 so that the numeral cylinder 106, and with its flange 107, transfer plate 115, and locking plate 114 are rotated while gear 102 (Figures 6 and 7) remains fixed. The shaft 107 is then shifted till pointer 151 is opposite counter wheel 104, and this wheel is similarly set in counter clockwise direction to the numeral five, the pawls 125 (Figures 9 and 10) riding over the notches in insert 127 to permit

the cylinder 106 and its flange 108, transfer plate 115 and locking plate 114 to rotate while gear plate 124 remains fixed. Counter wheel 105, is similarly set to the numeral 5. The indicators 89 and 90 are set to zero by means of ratchet set back knob 155, this motion being allowed by the friction drive between shaft 83 and gear 82, and the friction drive between shaft 84 and gear 85.

The predetermined counter being set at 555 the flow of liquid can now be started. To start the flow of liquid, the valve hand lever 29 (Figure 1) is depressed so that lug 25 engages against the end of stem 26, and the operating stem enlarged head 27 first engages valve guide rod 18 to open small valve 16 and relieve the pressure difference on the two sides of the valve, and then engages the hub of ribs 10 to open the large valve. The operating rod now is in the position shown in full lines in Figure 2. The forked lever 33 has been turned from its dot and dash line position by the engagement of cross pin 31 therewith, thereby causing the roller 35 at its opposite end to engage the curved portion 41 of the track on lever 36 and rotate lever 36 clockwise from its dot and dash line position. The rounded end 44 of lever 36 thereupon is brought into engagement with the straight side of recess 49 in lever 46 and turns this lever counter clockwise from its dot and dash line position, the rounded end of arm 50 of the lever riding over, and depressing the horizontal latch arm 55 of lever 53 as indicated by the dot and dash line position shown in Figure 3. The spring wire 59 on rock shaft 60 then returns lever 53 to the full line position shown in Figures 2 and 3 so that horizontal arm 55 engages and latches the arm 50 in retracted position as shown in full lines in Figure 2. When the opening lever 29 is released by the operator it rises by the action of spring 30 (Figure 1) but is not followed by the valve stem 26 because the lever stem is locked in its depressed position as lever 36 is locked against counter clockwise rotation by engagement of rounded end 44 with the straight portion 49 on lever 46, and lever 33 is locked against clockwise rotation by engagement of roller 35 against the straight portion 38 of the track on lever 36. Hence, the lever 33 holds the valves 9 and 16 in open position against the bias of spring 26, and the valve cannot close until the trigger latch arm 55 is rocked counter clockwise to release arm 46.

The flow begins through the meter as soon as the valve 16 is opened, and the operation of the meter turns shaft 73 and coupled shaft 75 which drives the unit pointer 90, through worm 81, worm wheel 82 and shaft 83, the sub total pointer 89 being secured to and driven by gear 88 which is driven through gear 87, on shaft 84, on gear 85, on shaft 84 and gear 86 on shaft 83. The totalizing counter 80 is driven from shaft 75 by bevel gears 77, 78 and shaft 79.

The worm 91 on shaft 75 drives worm wheel 92 on the predetermining counter drive shaft 93, which drives the counter wheels 103, 104 and 105 counter clockwise as reviewed in Figure 5 in descending direction through bevel gears 94 and 99 and drive gears 101 and 102. The units counter wheel 103 is first rotated by the positive engagement of pawls 118 on gear 102 with the internal ratchet wheel 121 on numeral cylinder 106 thereof. Each time counter wheel 103 makes a complete revolution, which corresponds to ten gallons, the notch 116 in transfer disk 115 and locking disk 114 receives a complete tooth of transfer pinion 122 and turns it the interval

between two mutilated teeth, and the teeth on pinion 122 engage gear disk 124 of counter wheel 104 to turn it one tenth of a revolution. The edge of locking disk 114 engages two complete teeth to lock the pinion 122 against accidental displacement as the counter wheel 103 continues to revolve. When wheel 104 makes a complete revolution the notch in its transfer disk 115 receives a complete tooth or transfer pinion 128 the teeth of which in turn engage gear disk 124 of counter wheel 105 and turn the latter one tenth of a revolution. The roller 136 (Figure 13) rides on flange 109 which has the greatest diameter and keeps the weight 130 in elevated position. When counter wheel 105 indicates zero the roller 136 falls into notch 112 leaving roller 135 riding on flange 108 until counter wheel 104 indicates zero, etc. Thus, a smaller force is required to drive the register than if all the rollers at all times engaged all the flanges. When all the counter wheels register zero, all the recesses 112, 111 and 110 respectively are in alignment and the rollers 136, 135 and 134 drop into the respective recesses thereby permitting weight 130 to drop, until stop screw 142 engages the top of bearing block 96. Through connecting rod 137 the dropping of the weight 130 rocks crank arm 138 secured to rock shaft 140, and by means of the coupling shaft 141 the trip arm 58 secured to rock shaft 60 is rocked clockwise as seen in Figure 3, thus rocking crank lever 53 counter clockwise to depress latch arm 55. The tripping of arm 55 releases arm 50, and the force of spring 22 now simultaneously closes valves 16 and 9 thus shutting off the flow when 555 gallons has been delivered. The upward movement of rod 26 places the levers 33, 36 and 46 in the dot and dash line positions shown in Figure 2. Should it be necessary to close the valves 16 and 9, before the full 555 gallons has been delivered the emergency plunger 64 is depressed and its inner end engages extension 57 and rocks lever 53 in tripping direction to release arm 50. When it is desired to reset the predetermining counter wheels, the wheels 103, 104 and 105 are individually set as previously described. This causes rollers 134, 135 and 136 to move out of their respective notches and raises weight 130 which, through connecting rod 137, rotates shaft 140 to return trip 58 to its full line position in Figure 3, the wire spring 59 returning latch lever 53 to its full line position ready for a resetting of the valve.

In the modification shown in Figures 13 to 20, the register housing 160 is exactly like the register housing 70 except as hereinafter described, and contains the predetermining counter mechanism. The bottom of the casing 160 seats on a casing 161 in which the trigger latch mechanism is housed, and which in turn is secured to the fluid meter in any suitable manner. The casing 160 can be rotated on case 161 to any desired position, clamping members 161' or other suitable means being provided for this purpose. The casing 161 comprises a bottom cup shaped recess 162, and a cover plate 163 therefor which is held in position by four screws 164 passing through the bottom casing 161 and threaded into the plate 163. The cover plate 163 has four guide posts 165 riveted thereto which have heads 166 at the upper ends thereof, and a thin disk or floating member 167 has holes therein loosely fitting over the guide posts 165 so that the plate 167 is capable of universal tilted longitudinal movement thereon as shown in Figure 17. The

bottom of the plate 162 carries a bent release plate 168 loosely pivoted on the line of bend by two headed pins 169, the flap being shown in one extreme position in Figure 13. A hole 171 is located in the bottom of the case 161, and the lower end of the tube 173 passes through the hole 171 and rests on one corner of the release plate 168, the tube extending through a hole 174 in the cover plate 163. The disk 167 rests on and is supported by the upper end of the tube 173. A pin 176 passes through suitable holes in the case 161 and top plate 163, and the lower end of this pin bears against a bent portion of the release plate 168 on the opposite side of the line of bend from the tube 173. An elongated weight 177 is loosely pivoted at one end by the headed pins 178 passing through enlarged holes in the weight, the weight having an enlarged hole 179 therethrough through which the tube 173 freely passes. In the position shown in Figure 13 the weight 177 bears on the pin 176 with the outer end 181 of the weight resting on plate 163, the opposite end 182 being in elevated position against the heads of the pins 178.

It will be evident, from the construction so far described, that the weight 177 bearing on the pin 176 depresses one end of the release plate 168, and the opposite end of the release plate 168 bears against the lower end of tube 173 holding it in elevated position and thus holds the disk 167 in its uppermost position as seen in Figure 13. The release plate 168 has a hole 183 therethrough terminating in knife edges 184 to provide a bearing edge for the lower end of tube 173. When the disk 167 is depressed, as will hereinafter appear, it forces tube 173 downwardly against release plate 168 whereby the release plate is pivoted on pins 169, this motion being allowed by the elevation of weight 177.

The case 161 is cut out at 191 and 192 to receive a slide bar 193 having a stop pin 194 extending therethrough at one end to limit its lengthwise movement therethrough. The bar 193 is cut out on its bottom as indicated at 195 and has a pin 196 driven therein which receives a roller or catch member 197 located in the recess 195. A curved lever 199 is pivoted on a headed pin 201 riveted to the bottom of the casing 161, and the lever 199 has a tail 202 which passes into the recess 195 in the slide bar 193. Adjacent the tail the lever 199 is cut out at 203 substantially on a circle to receive the roller 197, and it will be evident that upon sliding motion of the bar 193 to the right, that the roller 197 engages the corner 200 and swings the lever 199 about the pin 201 as a pivot in counter clockwise direction. Once the lever 199 has been moved in counter clockwise direction, its accidental return movement is prevented by a pin 204 sweated into the lever 199 which reacts with a bent guard 205 to maintain the lever in such position. Upon motion of the bar from right to left as seen in Figure 16, the roller 197 engages the tail 202 of lever 199 and swings the lever in clockwise direction, the guard 205 being moved out of the way of pin 204 to allow this movement.

The lever 199 carries a roller 206 pivoted on a pin 207 at the free end thereof. A second or intermediate curved lever 211 is pivoted on a shouldered pin 212 (Figures 16 and 18) riveted in the case 161 and carries a pin 213 at its opposite end, and it will be seen that the shoulder pin 212 and the pin 213 maintain the lever 211 elevated from the bottom of recess 162 so that it will contact with the roller 206. The lever 211

has a cut out portion 215 substantially conforming to the circumference of roller 206, and which terminates in a tail 216. It will be evident that when the lever 199 moves in counter clockwise direction it engages the edge of the groove 215 and swings the lever 211 outwardly or clockwise about the pivot pin 212, and when the lever 199 is rotated clockwise the roller 206 engages the tail 216 and rotates the lever 211 counter clockwise or inwardly about the pivot pin 212.

A third or latch lever 218 is pivoted in the case 161 by a headed pin 219, the pivot pins 212 and 219 being preferable but not necessarily substantially diametrically opposite. The latch lever 218 has a straight end portion 221 at its free end. Adjacent the pin 219 the latch lever 218 has a cut out portion 222 which is cut substantially on the circumference of roller 223 journalled on pin 213 in lever 211, and a cocking piece or tail 224 is provided adjacent the groove 222. When the lever 211 is rotated clockwise the roller 223 engages the end of groove 222 and rotates the latch lever 218 in a counter clockwise direction around the pivot pin 219, and when the lever 211 is rotated counter clockwise it engages the tail 224 and rotates the latch lever 218 in a clockwise direction about the pivot 219. A detent pin 227 (Figures 15, 16 and 19) is riveted or otherwise secured to one corner of the release plate 168 as shown in detail in Figure 19, and extends with a loose fit through a suitable hole 226 in the bottom of casing 161 into the latch chamber 162. This pin has a flat side portion 228 adjacent its end and the opposite side of the pin is cut on a bevel as indicated at 229. When the pin 227 is in elevated position the flat side 228 thereof is engaged by the free end 221 of lever 218 to prevent outward rotation thereof.

From the foregoing description it will be evident that when the bar 193 is in the position shown in Figure 16, the lever 211 will be in its position as shown, and the latch lever 218 will be in its full line position engaging detent pin 227. The bar 193 is thus locked against movement to the right in this position because the roller 223 engages the end of recess 222 of lever 218 while roller 206 engages the end of recess 215 of lever 211 and roller 197 engages the corner 200 of lever 199. As lever 218 cannot rotate it of course is not possible for levers 211 or 199 to rotate and the slide bar therefore is locked against movement to the right. This position of the bar corresponds to open position of the dispensing valve as will hereinafter appear. However, when the detent 227 is depressed, this action occurring automatically when the predetermined quantity has passed through the valve as will hereinafter appear, the latch lever 218 is allowed to rotate to the position shown in Figure 16 by dash and double dot lines, thus allowing roller 223 on lever 211 to clear recess 222 to allow lever 211 to rotate under urging of lever 199, and rotation of lever 211 releases roller 206 from recess 215 to allow lever 199 to rotate and clear corner 200 from the roller 197 thus allowing slide bar 193 to move to the right. The force for moving the bar 193 to the right preferably is provided by a spring in the valve itself as will hereinafter appear.

The dispensing valve is shown in Figure 14 in closed position. This valve comprises a casing 230 having a dividing wall 231 therein with a valve seat 232 against which a large valve 233

is adapted to seat. The valve member 233 has a smaller interior valve 234, and as the valves 233 and 234 are similar in construction with that shown in Figures 1 and 4, they will not be described in detail except where they differ therefrom. The valve 230 has an outlet 235 at one end, and the opposite end 236 is open and threadedly receives a cap 237 having a threaded inlet 238 therein. The cap 237 has four guide ribs 239 which are cut out at their center as indicated at 241 to receive the tubular extension 242 of the valve 233, and a hub 244 is formed at the terminal of the ribs 239. This hub has a bore 245 therethrough which receives the valve stem 246 secured to smaller valve 234, the ribs 239 being cut away at 247 to receive the end of spring 249. The opposite end of the valve 234 has an extension 251 which passes through a hole 252 in the hub 250 of the large valve 233.

The extension 251 is engaged by the end of a curved arm 255 which forms an operative connection with the squared end 253 of operating stem 256 of the valve (Figures 14 and 20). This stem extends through an offset chamber 257 through a suitable removable stuffing box assembly which comprises a removable stuffing box housing 258 threaded at one end with spaced threaded portions 260 and threaded home against the flange into the chamber 257. The bushing 258 has a packing recess 259 adapted to receive suitable packing which is compressed by a gland 261 threaded into the packing recess. Holes 263 are provided in the groove portion 264 to supply lubricant to the packing, and lubricant is supplied from the exterior to groove 264 through a suitable opening receiving a grease cup or other suitable device.

The squared end 265 receives an operating lever 267, and a hand wrench 268 is superposed thereon and held against removal in any suitable manner. The operating lever 267 has a hole adjacent its outer end and a connecting rod 269 with a clevis 271 at its end is secured thereto by a clevis pin 272. The connecting rod 269 has a similar clevis 273 at its opposite end (Figure 13) which is connected by a clevis pin 274 to one end of the slide bar 193.

The predetermining register is similar to that shown in Figures 1, and 5 to 12, except that rod 276 swiveled to the weight 130 has its lower end guided through a hole 275 in bearing bar 277 suitably secured to the frame 11. An emergency trip lever comprises a heavy ball 278 pressed onto the end of a trip pin 279 passing through a bushing 280 in housing 160. The weight of ball 278 normally holds the rod 279 in its upper full line position as shown in Figure 13. The shaft 75 has a gear 281 thereon at its lower end which meshes with a suitable gear not shown on a central shaft operated by the meter.

Referring to Figure 13, the operation of the meter rotates shaft 75 upon which worm 81 is secured, which in turn rotates worm wheel 82 and shaft 93 to operate the predetermining counter. This counter having been set to deliver any given quantity of fluid, the counter wheels 103, 104 and 105 (Figures 5, 6 and 13) are brought to the position where the notches 110, 111 and 112 are in alignment at the rear so that the rollers 134, 135 and 136 fall into these recesses and allow weight 130 to fall. The weight 130 pushes down rod 276 against the plate 167 depressing the same. The weight 171 which is pivoted at 178 bears on pin 176 and normally holds the right end of the release plate 168 de-

pressed as shown in Figure 13, and thereby maintains the detent pin 227 in elevated position as seen in Figure 19. The plate 167 bears on tube 173 which rests on one end of release plate 168. 5 When the rod 276 strikes plate 167 this plate is depressed thereby forcing the tube downwardly and depressing the left end of release plate 168 as shown in Figure 17 to depress the detent pin 227, this motion being permitted by the yielding of weight 171. The depression of detent 227 releases latch lever 218 allowing this lever to move counterclockwise to the position shown in dot and double dash lines (Figure 16), and allows roller 223 to clear recess 222 of the lever 218, whereby lever 211 is allowed to rotate clockwise. This in turn allows the roller 206 to clear the recess 215 of lever 211 whereby lever 199 is allowed to rotate counterclockwise to enable roller 197 to ride over the shoulder 200 which releases the slide bar 193 for movement from left to right. Slide bar 193 is attached to operating lever 267 of the valve 230 by the connecting bar 269, and movement of slide bar 193 to the right under the action of spring 249 allows lever 267 to rotate counterclockwise, thereby withdrawing curved arm 255 from engagement with extension rod 251 and allowing the spring 249 to close the valves 233 and 234 as shown in Figure 14.

The mechanism is set initially by the operator by turning the hand wrench 268 in clockwise direction to depress extension 251 and first open valve 234 against the action of spring 249. Upon further movement of wrench 268 the lever 267 engages the hub 250 of the valve 233 and causes this valve to open. The rotary movement of wrench 268 transmitted to stem 256 rotates operating lever 267 in clockwise direction, the movement of which is transmitted by the rod 269 to the slide bar 193 causing the slide bar 193 to be moved from right to left. It will be understood that the setting of the counter wheels 103, 104 and 105 to deliver a desired quantity of fluid as previously described, has raised the rollers 134, 135 and 136 out of the depressions 110, 111 and 112 so that they are riding on the flange 109 thereby maintaining the weight 130 and rod 267 in elevated position, the rod 276 being out of contact with the disk 167. This allows the weight 171 to depress the pin 176 to lower the right side of the release plate 168 from the position shown in Figure 17 to that shown in Figure 13 whereby the left end of the release plate carrying the pin 227 is elevated as seen in Figure 19, and the tube 173 and plate 167 are moved to their uppermost positions. Upon movement of slide bar 193 to the left the roller 197 engages the tail 203 of lever 199 and rotates this lever in clockwise direction whereupon roller 206 engages the tail 216 of lever 211 to rotate this lever in counterclockwise direction, and roller 223 engages the tail 224 of lever 218 to rotate this lever in clockwise direction. When the end 221 of lever 218 reaches pin 227 it rises and slides over the inclined edge 229, this motion being allowed by reason of a loose fit of pin 219 in lever 218. The flat side 228 of the detent pin prevents the lever 211 from returning until the pin 227 is depressed by operation of the automatic releasing means as previously described.

It will be noted that the hand wrench 268 is rotated against the action of spring 249, the tendency of this spring being at all times to close the valve. When the hand wrench 268 is released by the operator the tendency of the spring 249 to close the valve is transmitted through the

operating lever 267 and connecting bar 269 to the slide bar 193 causing this bar to move slightly to the right until the roller 197 engages the shoulder 200 on lever 199 whereupon further movement of the bar 193 to the right is prevented by the interengagement of levers 199, 211 and 218. The levers are then in the position shown in full lines in Figure 16.

Upon closing of the valves when the lever 199 has moved counter clockwise under the action of spring 229 it strikes the tube 173 and tends to rebound. However, by the time the lever 199 has rebounded the slide bar 193 has been moved to the right sufficiently to bring the guard 205 into such position that it is struck by the pin 204 carried on lever 199 thereby preventing this lever from striking tail 216 of lever 211 on the rebound and latching lever 218.

Should an emergency require shutting off of the valve 230, the operator raises the ball 273 thereby depressing pin 279 against the plate 167 to release the detent pin 227 as previously described.

The construction disclosed in Figures 13 to 20 has the advantage that the register case 160 may be turned at any angle to the latch housing 161, because the depressing of any part of plate 167 actuates the trigger release. Furthermore, it requires only a slight touch on plate 167 to set off the trigger mechanism due to the large leverage thereof.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:—

1. A control mechanism comprising a valve, a latch case, latch means in said case adapted to latch the said valve in open position, a trip mechanism including a non-rotatable universally tiltable plate, a predetermined register housing secured to said latch case, a register, and means connected to said register for operating said plate to trip said latch mechanism upon passage of a predetermined quantity of fluid through the valve to close said valve.

2. A control mechanism comprising a valve, a latch case, latching means in said case for latching said valve in open position, a trip mechanism including a centrally supported tiltable plate, means at the periphery of the plate limiting upward movement thereof and guiding downward movement thereof whereby said plate may be tilted at any position about its periphery, a housing secured to said latch case, predetermined counters in said housing, and means actuated by said predetermined counters to operate said plate to trip said latch means, whereby said valve is closed upon the passage of a predetermined quantity of fluid through the valve.

3. A control mechanism comprising a valve, latch means for maintaining said valve in open position comprising a series of interlocked levers, a detent for preventing unlatching movement of said levers, means maintaining said detent in restraining position, trip means including a universally tiltable member, and means operated by the passage of a predetermined quantity

of fluid through said valve for operating said universally tiltable member in tripping relation to release said detent.

4. A latch mechanism comprising a control case, a bar movable into said case, latch means for restraining said bar comprising a series of interlocking levers in said case, cocking means on said bar for engaging the first of said levers, a detent for preventing motion of the last of said levers, a release plate swivelly secured to said case and carrying said detent, a weight for maintaining said detent in restraining position, and a universally tiltable member bearing on said release plate and supported by said weight.

5. In a control mechanism, a valve comprising a large valve member having an opening therethrough, a smaller valve member adapted to close said opening, and spring means bearing against the smaller valve member to maintain both valve members closed, means to latch said valve members in open position, and means to trip said latch upon the passage of a predetermined quantity of fluid through the valve.

6. In a control mechanism, a valve comprising a large valve member having an opening therethrough, a smaller valve member adapted to close said opening and having a guide stem extending through said opening, an actuating rod adapted to first engage said guide rod to open the smaller valve member and then engage the larger valve member to open the same, spring means bearing against the smaller valve member and urging both valve members to closed position, means to latch said valve members in open position, and means to trip said latch upon the passage of a predetermined quantity of fluid through the valve.

7. A control mechanism comprising a latch case, a latch bar slidable in said case and adapted to actuate a valve, means biasing said latch bar in one direction, a catch member on said bar, series of interlocking levers pivoted in said case, the first of which is adapted to be engaged by said catch member, a detent for preventing motion of the last of said series of levers, a release plate swivelly secured to said case and supporting said detent, a pivoted weight, means connecting said weight and release plate for maintaining said detent in operative position, and a floating plate supported by said release plate and maintained in floating position by said weight.

8. A control mechanism comprising a bar adapted to actuate a valve, a catch member on said bar, a latch lever adapted to be engaged in latching position by said catch member upon movement of said bar in one direction whereby said bar is held in latched position, a guard member on said bar, and a pin on said lever to cooperate with said guard member whereby said lever is prevented from moving into latching position in unlatched position of said bar.

9. In a control mechanism, a latch case, a floating plate secured to said latch case and guided for tilting vertical movements, a release plate pivotally secured to said latch case, means for biasing said release plate in one direction, a spacer interposed between said release plate and floating plate whereby said floating plate is supported by said release plate, a pivoted weight biasing said release plate in one direction, a movable member adapted to operate a valve, latch means maintaining said member in one position, the movement of said release plate serving to release said latch means.

10. A control mechanism comprising a pivoted

lever having a cocking piece, at least one additional pivoted lever having a cocking piece and having a portion engaging the cocking piece of the first lever; a member adapted to operate a valve and having a portion adapted to engage the cocking piece on one said additional lever whereby movement of said member in valve opening direction successively cocks said levers, a detent for maintaining said levers in cocked position, means urging said member into valve closing position, and a predetermining mechanism for releasing said detent.

11. A control mechanism comprising a valve, a latch case, a latched member movable into said case and connected to said valve, latching means for said member to maintain said valve in open position, a detent preventing unlatching movement of said latching means, a centrally supported plate extending substantially completely around the center, a weight for maintaining said detent in locking position and biasing said plate in one direction, predetermining means, and means operated by said predetermining means to depress said plate for releasing said detent to permit movement of said member to valve closing position.

12. A control mechanism comprising a fluid meter, a valve connected in the fluid line of said meter, a latched member connected to said valve, means to bias said latched member in valve closing direction, a series of interconnected levers pivoted on parallel axes arranged about a common center and including a latching member engaging said latched member and adapted to be forced out of latching engagement by said bias-

ing means, detent means for preventing movement of the last of said series of levers, means for actuating said detent including a member passing through said common center, and predetermining means for operating said detent actuating means for releasing said latched member upon the passage of a predetermined quantity of fluid through the meter.

13. A control mechanism comprising a fluid meter, a valve connected in the fluid line of said meter, a bar connected to said valve, means to bias said bar in valve closing direction, a series of interconnected levers including a latching lever having a portion engaging said bar, detent means for preventing movement of the last of said series of levers, and predetermining means for releasing said detent upon the passage of a predetermined quantity of fluid through the meter.
14. A control mechanism comprising a valve, a latched member connected to said valve, latching means for said member to maintain said valve in open position and including a plurality of interlocked levers arranged to provide a mechanical advantage for said latching means, a detent preventing unlatching movement of said levers, predetermining means, an independent force means for tripping said detent maintained in potential position by said predetermining means, and means for releasing said independent force means to trip said detent and permit movement of said member to valve closing position.
